UNITED STATES PATENT OFFICE.

WILLIAM MOONEY, OF NORTH PLAINFIELD, NEW JERSEY, ASSIGNOR OF ONE-HALF TO JAMES R. FLOYD & SONS, OF NEW YORK, N. Y.

ROTARY GAS-SCRUBBER.

SPECIFICATION forming part of Letters Patent No. 444,300, dated January 6, 1891,

Application filed July 12, 1890. Serial No. 358,492. (No model.)

To all whom it may concern:

Be it known that I, WILLIAM MOONEY, of North Plainfield, in the county of Somerset and State of New Jersey, have invented a new and useful Rotary Gas-Scrubber, of which the following is a full, clear, and exact description.

This invention relates to improvements in gas-scrubbers of the rotary type wherein the gas is introduced and made to impinge on wet surfaces to remove impurities.

My invention further consists in the construction and combination of parts, as hereinafter described and claimed.

Reference is to be had to the accompanying drawings, forming a portion of this specification, in which similar letters of reference indicate corresponding parts in all the figures.

Figure 1 is a side elevation, partly sectional, of the scrubber, showing one division or compartment of the casing provided with dashers revolvably mounted upon a center shaft. Fig. 2 is a partly-sectional plan view taken on the line 2 2 in Fig. 3. Fig. 3 is a transverse section with the dashers removed, taken on the line 3 3 in Fig. 2. Fig. 4 is a longitudinal section of one gas-compartment in the scrubber enlarged, taken on the line 4 4 in Fig. 5. Fig. 5 is a transverse sectional elevation of one segmental portion of a washer-compartment in the scrubber; and Fig. 6 is an enlarged broken sectional view of two dashers and spindles between the dashers, showing the relative position of the spindles with regard to the perforations in the dashers.

The outer casing of the scrubber, as shown, consists of a rectangular tank A and a cover-section A', having side wings or extensions C, which extend along the sides, which wings are connected by a segmental top or cover e. The casing is divided by transverse partitions g into equal-sized compartments D, the partitions extending across the wings C and being provided in the wings with openings p at alternate ends nearly the size of the cross-section of the wing. At diagonally-opposite corners of the casing the wings are provided, respectively, with an inlet and an outlet opening F and G.

As shown, the casing consists of a base-plate, to which are secured the end pieces g'

and the sectional side pieces g², provided with side flanges a², a marginal flange c extending around the upper edges of the end and side pieces, these parts forming the body of the tank A. The partitions g are secured to the base-plate and between the flanges a², and in marginal contour conform to the cross-section of the completed casing. Upper end pieces g³ complete the ends. Angle or L-shaped pieces a', provided with flanges c², rest on the flange c of the side pieces g² between the partitions g and between the partitions and end pieces. Segmental cover-plates e, flanged and united at e² and provided with straight end portions e', rest on the upper flanged ends of the angle-pieces c' between the partitions g, the whole being secured together in any suitable manner; but the casing may be constructed in any approved manner.

A shaft B, supported in brackets a, secured to the ends of the casing, extends longitudinally of the casing about centrally thereof, passing through stuffing-boxes a' in the casing ends to prevent the leakage of gas, and through thimbles a³ in the partitions g. The shaft is provided at one end with a driving-pulley B'. On the shaft B between the partitions are fixed hubs h, having polygonal rims h', which each support two parallel spaced disks i close to the partitions g, which disks are provided on their inner sides with radial ribs i', the pair of disks in each compartment forming a hollow wheel fitting closely in the compartment and adapted to revolve therein.

The hollow wheels support segmental scrubbing-frames I, consisting of segmental side plates i², adapted to fit between the ribs i', and of perforated dasher-plates m, preferably of wood, parallelly arranged and extending between the plates i² at right angles therewith, as shown. The perforations m' of the dashers m are arranged in spaced rows, and between the dashers aligning the perforations m' therein are arranged rows of spindles n, held in the plates i², so that currents of gas passing through the perforations m' will impinge upon the spindles and be divided, as shown in Fig. 6.

At a proper point, preferably on one end of the casing, is a water-inlet pipe H, said pipe

being bent to produce a trap to prevent escape of gas, and at the opposite end, at a point aligning the bottoms of the openings p in the partitions g , is a trapped outlet-pipe I' , by which location of the outlet the tank A will be kept full of water.

- The shaft B , with the wheels carrying the scrubbing-frames, being revolved, gas entering the scrubber through the inlet-pipe F traverses the first compartment D through the revolving wheel in the direction of the arrow y . It then passes through the opening p in the first partition into the second compartment D , passing through the wheel in said compartment in the direction of the arrow y' , whence the gas passes through the remaining compartments in the direction of the arrows 1, 2, and 3.

The gas in its passage through the perforations of the dashers of the scrubbing-frames and against the spindles, which are all kept wet by their immersion as the wheels revolve in the water in the tank A , will be thoroughly purified, and as the peripheries of the wheels closely fit the top or cover of the casing the gas is compelled to pass through the scrubbing-frames.

By the frictional contact of the gas with the wet scrubbers tarry matter not previously taken out will be mechanically removed, and at the same time any ammonia and carbonic acid remaining in the gas will be taken up by the water.

From the peculiar construction and arrangement of this device it is apparent that a large frictional area is afforded for impinging contact of the gas, as the gas enters and passes through the revolving scrubbers at right angles to their axis of revolution.

While it is preferred to use the spindles n , 40 they may be dispensed with, and an increased number of dashers m be used with good results.

Having thus described my invention, what I claim as new, and desire to secure by Letters 45 Patent, is—

1. In a gas-scrubber, a scrubbing-frame consisting of two parallel-spaced segmental plates i^2 , a series of transverse parallel foraminated plates m , and a series of rods or spindles between each pair of foraminated plates and in line with the opposing perforations $m' m'$ therein, as shown and described.

2. A gas-scrubbing machine consisting of the tank A , having a curved top A' , opposite longitudinally-extending side wings or extensions C , transverse partitions g , conforming in marginal contour to a transverse section through said tank, top, and wings and having openings p at alternate ends within 60 said wings or extensions, inlet F and outlet G , a longitudinal shaft B , and scrubbing-wheels on the said shaft, one for every compartment, and each consisting of two circular plates i^2 , having radial ribs $i' i'$, segmental frames seated between plates i on said ribs and formed of parallel segmental plates i^2 , transverse parallel foraminated plates m , connecting the plates i^2 , and rods or spindles n , between the foraminated plates and in line 70 with their opposed apertures, the said wheels fitting closely the sides and curved top of the several compartments, substantially as set forth.

WILLIAM MOONEY.
